UNITED STATES PATENT OFFICE.

SAMUEL J. HINES, OF PLAQUEMINE, LOUISIANA.

LIFE-PRESERVER.

1,137,971.

Specification of Letters Patent.

Patented May 4, 1915.

Application filed May 5, 1914. Serial No. 836,525.

To all whom it may concern:

Be it known that I, SAMUEL J. HINES, a citizen of the United States, residing at Plaquemine, in the parish of Iberville and State of Louisiana, have invented new and useful Improvements in Life-Preservers, of which the following is a specification.

The invention relates to life preservers, and more particularly to the class of life preserving garments.

The primary object of the invention is the provision of a garment of this character wherein the same is formed with an opening to permit the wearing of the garment without possibility of water creeping into the same, thus protecting the wearer and also permitting the convenient application or removal of the garment.

Another object of the invention is the provision of a garment of this character wherein the wearer will be sustained afloat and protected from water, the material of the garment being water proof, and affording the wearer freedom of movement while wearing the garment, the garment being of novel form to insure service.

A further object of the invention is the provision of a garment of this character wherein the same when not in use can be readily folded to render it compact so that it will occupy the least possible space, and also which is simple in construction, reliable and efficient in its purpose, and inexpensive in manufacture.

With these and other objects in view, the invention consists in the construction, combination and arrangement of parts as will be hereinafter fully described, illustrated in the accompanying drawings, and pointed out in the claim hereunto appended.

In the drawings:—Figure 1 is a front elevation of a garment constructed in accordance with the invention. Fig. 2 is a rear elevation thereof. Fig. 3 is a sectional view. Fig. 4 is an enlarged vertical sectional view through the garment. Fig. 5 is a fragmentary vertical sectional view through one of the buoyant elements. Fig. 6 is a top plan view of the garment.

Similar reference characters indicate corresponding parts throughout the several views in the drawings.

Referring to the drawings in detail, the garment comprises a body portion A, leg portions B, sleeve portions C, the latter be-

ing formed with hand coverings D, each provided with a thumb stall E, while the leg portions B are formed with foot coverings F, which are integral therewith, and likewise the hand coverings D are integral with the sleeve portions C of the garment. The garment is made with front and back sections 5 and 6 respectively, the same being joined together with overlapped uniting seams 7 which are water-proof, the sections being also made from suitable water-proof material, such for example as water-proofed canvas with a rubber coating.

The body A is formed with an enlarged neck opening 8 adjacent to opposite edges of which are formed eyelets 9 through which is trained a lacing 10 so that the neck opening can be varied in size to fit tightly about the neck of the user of the garment. When it is desired to fit the garment to a person the feet and legs of such person are passed through the neck opening 8 and the garment is pulled upwardly a suitable distance, and then the arms are inserted in the sleeves C. After the garment has received the body, the lacing 10 is drawn to fasten the garment about the neck of the wearer.

Stitched or otherwise secured exteriorly to the body A of the garment, at or above the waist line, is a water-proof casement 11 in which is fitted a pneumatic inner tube 12 formed with the usual valved filling stem 13 which projects through the casement 11 to the exterior thereof so that an air pump can be attached to the stem 13 for the filling of the inner tube 12 with air to expand the casement 11 to serve as a buoyant element. Fixed between the body 10 and the casement 11 at intervals are straps 14 to which are detachably connected in any suitable manner spherical bodies 15 which are made from water-proof material and in which are fitted inflated balls 16 provided with valve stems 17 which project through the bodies 15 exteriorly thereof to permit the detachable connection of an air pump therewith. These bodies 15, together with the inflatable balls 16 therein serve as buoyant elements for the garment, and will assist with the casement 11 having the tube 12 therein for sustaining the wearer of the garment afloat. Suitably connected to the neck portion of the body A of the garment is a head covering 18 which can be worn by the user for preventing the wetting of the head.

What is claimed is:—

A life preserver comprising a water-tight garment forming a body portion, leg portions and sleeve portions, hand and feet coverings integrally formed with the respective sleeve and leg portions, a casing formed without the body portion at the waist line thereof, an inflatable buoyant element located within the casing, flexible straps mounted on the body portion immediately

below the casing and being of a length to depend a distance below the waist line of the body portion, and inflatable buoyant elements carried at the free ends of said straps.

In testimony whereof I affix my signature 15
in presence of two witnesses.

SAMUEL J. HINES.
